CLAIM

The ornamental design for a light therapy apparatus, as shown and described.

DESCRIPTION

FIG. 1 is a front side elevational view of an embodiment of the light therapy apparatus of the present design, with the stabilizer portion partially extended;

FIG. 2 is a rear side elevational view of the light therapy apparatus of FIG. 1, with the stabilizer portion partially extended;

FIG. 3 is a top side elevational view of the light therapy apparatus of FIG. 1, with the stabilizer portion partially extended;

FIG. 4 is a right side elevational view of the light therapy apparatus of FIG. 1, with the stabilizer portion partially extended;

FIG. 5 is a left side elevational view of the light therapy apparatus of FIG. 1, with the stabilizer portion partially extended;

FIG. 6 is a front side, right side, and top side perspective view of the light therapy apparatus of FIG. 1, with the stabilizer portion partially extended;

FIG. 7 is a front side, right side, and top side perspective view of the light therapy apparatus of FIG. 1, with the stabilizer portion not partially extended;

FIG. 8 is a right side elevational view of the light therapy apparatus of FIG. 1, with the stabilizer portion not partially extended; and,

FIG. 9 is a left side elevational view of the light therapy apparatus of FIG. 1, with the stabilizer portion not partially extended.

The broken lines of FIGS. 2-8 are for the purpose of illustrating structure of the light therapy apparatus that form no part of the claimed design and that are unclaimed subject matter.
